TUBE FORMING TOOL

James Fentress, Hubbard Woods, Ill., and Albert Dreyer, Lucerne, Switzerland, assignors to Chicago Metal Hose Corporation, Maywood, Ill., a corporation of Illinois

Application October 17, 1936, Serial No. 106,242
In Switzerland February 11, 1936

5 Claims. (CL 153—32)

This invention relates to a tool or die for forming thin walled or flexible tubing from thin sheets of metal. The object of the invention is to provide a simple, inexpensive and efficient tool 5 for forming such tubing from thin sheets of metal.

In the tube forming dies of the prior art the friction set up by the engagement of the sheet to be formed with the walls of the die was variable and therefore the speed with which the sheet was drawn through the die was likewise variable. This lack of constant speed resulted in the formation of kinks and in the improper welding of the seam of the completed tube. In drawing the 5 sheet material through these dies, the friction thus set up consumed an unnecessarily large amount of power.

The configurations of these dies were such that the axis of the tube during its formation was 10 below the axis of the completed tube and this caused a stretching of the tube along its seam edges.

It is an object of this invention to provide a forming tool or die which materially decreases 15 the friction between the sheet of metal being formed and the die, and which therefore permits the sheet of metal to be drawn through the die at a substantially constant speed and without kinking.

Another object of the invention is to provide a forming die in which the power required to pull the sheet of metal through the forming tool is reduced to a minimum.

Another object of the invention is to provide 15 a tube forming die which delivers the completed tube in accurate form for proper welding.

Another object of the invention is to provide a forming tool or die in which the sheet being formed is positively retained in the die.

Another object of the invention is to provide a tube forming tool or die of such configuration 20 that the metal sheet when drawn through the die will not be caused to stretch.

Other and further objects of the invention will 25 be apparent throughout the progress of the specification.

The accompanying drawing illustrates selected 30 embodiments of the invention and the views therein are as follows:

Fig. 1 is a plan view of one preferred embodiment 35 of the tube forming die, a part of the die being shown in section.

Fig. 2 is a side elevation of the die, a portion 40 being shown in section.

Figs. 3, 4, 5 and 6 are cross sections of the 45

die taken along lines 3—3, 4—4, 5—5 and 6—6, respectively, of Fig. 2.

Fig. 7 is a plan view of a modified form of the die.

Fig. 8 is a side elevation of the die of Fig. 7.

Figs. 9, 10, 11, 12 and 13 are cross sections of the die taken along the lines 9—9, 10—10, 11—11, 12—12 and 13—13, respectively, of Fig. 8.

In the preferred embodiment shown in Fig. 1 the tube forming tool or die comprises a sheet 10 metal channel member 1 and a tube or draw ring 2. The member 1 is fastened to the draw ring 2 by pins 5 which are fastened to the member 1 and engage in apertures 6 in the draw ring. The draw ring 2 is provided with a frusto-conical aperture or passage 3 and a cylindrical aperture or passage 4, the base of the frusto-conical portion or aperture 3, which is the largest diameter, being in registry with the reduced end of the forming member 1, and the cylindrical aperture 20 4 being at the opposite end of the draw ring 2 and registering with the reduced end of the frusto-conical aperture 3.

The forming member 1 at its outermost end or edge portion 7 is substantially flat in cross section, as shown in Fig. 3. From its outermost end the bottom of the channel member 1 progressively and uniformly increases in distance below the axis A—A and the sides uniformly and progressively approach the axis B—B to form at its end 25 adjacent the draw ring 2 a substantially V-shaped channel, as shown in Fig. 4. During its passage through the channel member 1 the axis of the tube being formed is coincident at all positions with the axis of the completed tube as it is drawn from the cylindrical aperture 4. The axis of the frusto-conical section 3 of draw ring 2 is similarly coincident with the axis of the cylindrical aperture 4 and the completed tube drawn therefrom. The channel member 1 is provided with upturned 30 and inturned flanges 8 at its upper edges to retain the sheet in the channel while being drawn therethrough.

As a sheet of metal is pulled or pushed through the die from the outer flat end or edge portion 7 of the channel member 1 its edges gradually and uniformly are turned inward toward the axis of the channel and its surface gradually and uniformly is caused to assume the configuration of a tube. As the metal being formed passes 45 through that portion of the channel member shown in cross section in Fig. 4, it assumes the configuration of a U- or V-shaped tube whose edges are turned inwardly and engage with the inturned flanges 8 of the channel member and 50 55

whose sides engage the sides of the V-shaped channel member.

In its passage through the conical aperture 3 of the draw ring 2 this substantially U- or V-shaped tube is formed first into an open-seam cylindrical tube by gradually forcing its bottom portion upwardly and its edge portions inwardly. As it progresses still further through the aperture 3, the seam is gradually closed until, as it 10 is drawn into and through the cylindrical aperture 4, the seam is closed or the edges are overlapped.

In the form shown in Figs. 7 to 13, the tube forming tool or die is made of a single integral sheet of metal 9 having an edge portion 10 substantially flat in cross section and a portion 11 of gradually increasing cross section in a vertical direction and of gradually decreasing cross section in the horizontal direction. This sheet 20 metal member 9 has also a frusto-conical portion 12 of a cross section gradually decreasing from the portion 11 and a portion 13 of cylindrical cross section. The channel member 9 is provided, similarly to the channel member 4, with upturned and inturned edges 14 for the purpose of retaining the material being formed in the channel member. During its passage through the forming member 9, the axis of the material being formed is coincident at all positions with 30 the axis of the completed tube as it is drawn from the cylindrical portion 13.

The operation of the tube forming tool or die of Figs. 7 to 13 in forming a tube from a thin sheet of metal is the same as that described in 35 connection with the two-piece die of Figs. 1 to 6.

It has been found that with the tube forming die of this invention the loss of power due to friction has been greatly reduced over that encountered with devices of the prior art. It has 40 been further found that with this die the material exhibits no tendency to stretch or kink as was found to exist in connection with devices in use prior to this invention and that the seam edges of the completed tube drawn from this die 45 are in accurate engagement for proper welding.

Changes may be made within certain degrees in the form, construction, and arrangement of the parts and the right is hereby reserved to make all such changes as fairly fall within the 50 scope of the following claims.

Having thus described the invention, what is claimed to be new and desired to be secured by Letters Patent is:

1. In a die for forming a tube from flat sheet material, a forming device comprising a first

portion having a shaping surface arranged in a generally conical plane, a second portion having the general form of a trough and extending to the larger end of the shaping surface of said first named portion, said second portion gradually increasing in height and decreasing in width in the direction of said first named portion and being arranged with respect to said first portion in such a manner that the bottom of the trough diverges from an extension of the axis of said 10 shaping surface in the direction of said first mentioned portion.

2. In a die for forming a tube from flat sheet material, a forming device comprising a first portion having an interior shaping surface arranged in a generally frusto-conical plane and a second portion having the general form of a trough and being arranged with one end in juxtaposition to the said shaping surface of the first named portion, said second portion having its 20 other end of generally flat cross section, and increasing in height and decreasing in width in the direction of said first mentioned portion, and being arranged with said first mentioned portion in such a manner that the bottom of the 25 trough is inclined with respect to the axis of the shaping surface and diverges therefrom in the direction of said first mentioned portion.

3. The die defined in claim 2, wherein the said second portion of said forming device is provided 30 with flanges projecting upwardly from a portion at least of its side edges to retain the material being formed in the forming device during passage therethrough.

4. The die defined in claim 2, wherein a cylindrical forming portion is arranged in juxtaposition to the smaller end of said frusto-conical 35 shaping surface.

5. In a die for forming a tube from flat sheet material, a forming member comprising a unitary piece of sheet material having a first portion configurated to provide an interior shaping surface arranged in a generally frusto-conical plane, a second portion having the form of a trough and extending from the larger end of said 40 frusto-conical surface, said second portion gradually increasing in height and decreasing in width in the direction of said first mentioned portion and being arranged with respect to said first portion so that the bottom of the trough is inclined with respect to the axis of said frusto-conical surface and diverges therefrom in the direction of said first mentioned portion.
